UNITED STATES PATENT OFFICE.

WILLIAM J. DAVIDS, OF AMSTERDAM, NETHERLANDS.

APPARATUS FOR MAKING DOPS TO HOLD PRECIOUS STONES DURING GRINDING OR POLISHING.

1,400,423.

Specification of Letters Patent. Patented Dec. 13, 1921.

Application filed December 17, 1920. Serial No. 431,463.

To all whom it may concern:

Be it known that I, WILLIAM JOSEPHUS DAVIDS, a subject of the Queen of the Netherlands, residing at 75 Weesperzyde, Amsterdam, Netherlands, have invented certain new or Improved Apparatus for Making Dops to Hold Precious Stones During Grinding or Polishing, of which the following is a specification.

10 This invention has reference to apparatus or appliances for use in making the cast-metal dops that are employed for holding diamonds and other gems or precious stones during the operations of grinding or polishing.

In order to properly secure a stone in the apex of a cast conical dop, the said stone must be accurately set or positioned in the center of the opening at the small or apex 20 end of the conical matrix of the casting mold, and firmly held in that position during the running-in or pouring of the molten dop-metal, so that the metal at the apex of the dop may run around the girdle of the 25 stone and secure the latter in the appropriate position, *i. e.* with the portion to be ground or polished projecting beyond the end of the dop.

Absolute accuracy in the centering of the 30 stone in the mold is essential in order to insure that the axis of the stone shall coincide with the axis of the dop, as otherwise it would be impossible subsequently to geometrically grind the required facets on the 35 stone, and for the same reason, it is essential that after the stone has been centered in and with relation to the apex opening of the mold, it should be rigidly held against any possibility of displacement during the 40 running in of the metal for casting the dop around the girdle of the stone.

In the accompanying drawings I have shown an apparatus constructed in accordance with my present invention, which enables the above-mentioned essentials to be realized, and which also has the further and most important advantage that it embodies a self-contained "setting tool" which is independent of, but attachable to, the mold, 45 or casting part of the apparatus, and provides for the operation of centering the stone being performed away from the mold and in full and convenient view or observation of the operator; the construction of 50 this setting tool and its complementary parts

in the mold being such that when the tool, with the previously-adjusted stone held therein, is applied to the said mold, the said stone is positively and automatically positioned in truly central and perpendicular 60 relationship to the mold axis, without further adjustment being necessary. The apparatus thus enables the setting of the stones and the casting of the same into dops to be carried out more expeditiously and exactly, and in a more commercially economic manner, than is possible with any known dop-casting machine, since a number of setting tools can be used interchangeably in conjunction with one mold, and the setting 65 70 of stones in these tools can be effected by one operator or set of operators while the actual casting can be performed by another operator who, as soon as one dop has been made and removed with the stone from the mold, 75 can have another (cold) setting tool, with the stone properly held and centered therein, ready to be placed within the mold for casting the next dop.

In order to provide for the setting operation to be performed outside or away from the mold, the dop-casting apparatus in accordance with my said invention comprises two distinct and self-contained parts or units, one of which contains the casting 80 mold and chuck mechanism whereby the stone is actually held during the casting operation, while the other unit serves as the setting tool wherein the actual setting of the stone is performed away from the mold 85 and whereby also the set stone is positioned or located in the mold matrix prior to being gripped by the chuck mechanism; the essential feature of the setting-tool unit being that it embodies a member which is adapted 90 to be positioned (when the tool unit is applied to the mold unit) transversely across the mold matrix and is formed with a gap or clearance (hereinafter referred to as the gaging gap) whose shape is a counterpart 95 or replica of the transverse sectional shape of the said matrix. The setting pins of the tool are so arranged in relation to this gaging gap that they provide for the adjustment of the stone in the axis of the said gap in the same relative position as the 100 said stone is required to subsequently occupy in the mold-matrix, while the gap is so disposed in the setting tool member that when the tool is applied to and located on 105 110

the mold-unit, it (the gap) will register exactly with the matrix and consequently position the stone correctly in the axis of the latter.

5 In the said drawings,

Figure 1 is an elevation of my apparatus, showing the setting tool applied and secured to the mold ready for the casting operation.

10 Fig. 2 is a plan of Fig. 1. In these views the upper arm of the setting tool is broken away, to exhibit the other parts more clearly.

15 Fig. 3 represents, on a large scale and partly in section and partly in elevation, the two main parts of my apparatus. This view shows the setting tool disconnected and separated from the mold to permit of the setting operation being performed away from the said mold and in full view of the operator.

20 The mold unit is drawn in section on the dotted line 3—3, Fig. 6, and it should be pointed out that in this figure, two jaws of the chuck mechanism are drawn as though they were located in the same plane as the 25 slot in which the bottom-blade of the setting tool is seated. This, however, is only done for the purpose of clearly showing the form and construction of the chuck mechanism; the jaws being actually located in 30 slots disposed at an angle to the setting tool seating as shown in Figs. 5 and 6.

Fig. 4 is a similar view to Fig. 3, but shows how the setting tool is applied to the mold for enabling the centered stone to be 35 gripped and held, during the actual casting of the dop, by a chuck mechanism which is embodied in the said mold.

Fig. 5 is a plan of the mold, showing the relative dispositions of the slots or clearances provided therein for the accommodation, respectively, of the detachable setting tool and of the jaws of the chuck mechanism.

40 Fig. 6 is a plan of Fig. 4.

Fig. 7 is a view showing how, after the 45 setting tool has been applied to the mold and the stone has been gripped by the mold-chuck, the upper arm of the said tool is turned into the position indicated, in order to allow for the placing of the pouring gate 50 on the top of the mold.

The same letters of reference indicate corresponding parts in the several figures of the drawings.

55 In the apparatus illustrated, the mold-unit comprises a mold and its supports, chuck-mechanism for gripping a stone around its girdle during the casting operation, and means for supporting and registering the setting-tool whereby the previously-adjusted 60 stone is introduced into and positioned in the mold-matrix preliminary to the same being taken hold of by the chuck mechanism.

65 The mold *a* is elevated on a suitable stand or frame, with the larger end of its conical matrix *a'* uppermost, and is arranged so that

a detachable pouring gate *b* (see Fig. 7) can be applied to the top of the same to facilitate the running in of the dop metal. The lower or apex end of the matrix has an aperture or opening *a²* of suitable size, in the center 70 of which the stones are first placed by the setting tool and then held by the chuck, and four vertical slots *c* are cut into the lower part of the mold, at an angular separation 75 of ninety degrees, to accommodate and provide working clearances for the jaws of the chuck. These slots (as will be seen from the separate plan-view of the mold, Fig. 5) all open at their inner sides into the bottom aperture of the mold, and they are also open 80 at their bottom ends to allow for the jaws of the chuck (which is located underneath the mold) extending upwardly into their respective working clearances.

85 Another vertical slot *d* is cut across the diameter of the mold, and between the chuck-jaw clearances *c* (in the relative position to the latter as shown in Fig. 5) to accommodate or form a seating for the bottom blade *s'* of the setting-tool unit. This seating is cut right through the wall of the mold on one side of the matrix to enable the bottom blade of the setting tool (when *in situ* in the mold) to extend into connection with its external support, whereas on the opposite side of the said matrix, the seating slot is cut only a sufficient distance into the mold walls to afford an adequate bearing for the inner end of the said bottom blade (see Figs. 4 and 7).

90 On the outside of the mold-stand is a rigid bracket *e* formed with a vertical socket or seating *e'* for the reception of the setting-tool standard *s²*; this socket being disposed so that its center comes exactly in the same 95 plane as the center of the matrix aperture and the center line of the transverse seating-slot *d*.

95 The chuck mechanism, as has already been stated, is disposed underneath the elevated mold, and comprises four blade-like jaws *f* having an angular separation of ninety degrees and mounted on the upper-ends of levers *g* that swing from fulcra in the base 100 of the mold-stand and are capable of angular movements in their respective jaw clearances *c* in the mold; the said levers being operated or controlled by suitable mechanism whereby the inner edges of the blades are (after the position of a stone in the apex 105 aperture of the mold-matrix by the setting tool) closed toward one another and made simultaneously to project into the said aperture and to grip the said stone at four equidistant points around its girdle so as to 110 centrally support the same during the casting operation, after which the chuck jaws are separated or opened apart to release the stone and permit of the latter being lifted 115 out of the mold with the dop.

Any suitable mechanism may be used for importing the necessary simultaneous and equal angular motions to the chuck-levers for closing together or opening out the jaw-blades. In the apparatus shown in the drawing, however, this mechanism consists of a horizontal cam plate or frame h having four holes or slots h' disposed at the same angular separation as the chuck-levers, which are set at an inward inclination to the center of the said plate, and are each passed through one of the holes or slots so that the lowering of the plate will compel the levers to close toward one another while the reverse movement will cause them to separate. The center of the plate is connected to a vertical screw i which engages with a rotatable nut i' that has its bearing in base of the mold stand and is rotatable, by bevel or other bearing, from a hand-wheel conveniently disposed on the outside of the stand; the arrangement being such that by turning the hand-wheel one way or the other the cam-plate is either raised or lowered for effecting the closing or opening of the chuck as desired.

To describe now the setting-tool unit s of the apparatus: this is a self-contained structure which is applied to the mold only after the setting of the stone has been effected, and it comprises a bottom blade s' carrying an adjustable bottom centering-pin s^3 , a hinged arm s^4 carrying an adjustable top centering-pin s^5 and a supporting standard s^2 by which the tool is connected or attached to the bracket e on the mold-stand, for which purpose the base of the said standard is formed as a peg s^6 suitable for dropping into the vertical socket in the bracket.

The bottom blade is rigidly connected with the standard and fixed exactly at right angles thereto. It consists of a metal plate adapted to be inserted from the top into, and to closely and accurately fit within, the bottom-blade seating slot d of the mold, and of such a length that, when positioned across the mold matrix, its inner end abuts against the inner end of the seating-slot, as shown in Figs. 4 and 7.

The inner portion of the top side of the blade is formed with a V-shaped gaging-gap s^7 which is a counterpart or replica of the cross sectional shape of the mold-matrix; (see the chain-dotted lines in Fig. 3) the sides of the same having an angle corresponding to pitch or inclination of the sides of the matrix, while the disposition of the gap in the blade is such that when the tool is applied to and properly located on the mold, its edges register with the sides of the said matrix. Consequently a stone which has been correctly adjusted in and relatively to the small end of the gaging gap by the setting tool prior to the said tool being

mounted in the mold will, of necessity, occupy the same relative position in the apex aperture of the matrix when the two parts or units of the apparatus are assembled.

At the bottom of the gaging is a small rectangular clearance s^8 which is of a width not less than the diameter of the bottom aperture a^2 of the mold matrix, and whose vertical sides preferably have knife or feather edges. This clearance is the setting-tool counterpart of the said matrix aperture, and has located centrally within it, a fine-threaded screw s^9 , which constitutes the bottom setting-pin and is vertically adjustable in a wormed hole through the blade to provide for the position of the top end of the pin being raised or lowered in relation to the bottom end of the gaging-gap during the operation of setting the stone.

The hinged arm s^4 that carries the top setting-pin s^5 is hinged at the extremity of its cranked outer end s^9 to a part of the bottom-blade that is extended outwardly beyond the supporting standard, while the top setting pin is carried at its other extremity in such a position that, when the hinged arm is swung over to bring the same into parallel relationship with the fixed bottom blade, the top and bottom setting pins s^5, s^9 , are in exactly the same alinement to admit of a stone being held and centered between opposite ends. Provision is also made for locking or fixing the hinged arm to the attachment standard after the stone has been centered and prior to the tool, with stone in position, being transferred to the mold, for which purpose, a slot s^{10} may be cut across the crown of the standard, so that on the hinged arm being swung over, a portion of the horizontal limb enters the cross-slot and is there secured by passing a locking-pin s^{11} through registering holes in the standard and arm.

The shank of the setting-pin s^5 is slidable in the hinged arm and is influenced by a suitably-applied spring s^{12} tending constantly to depress the pin, and in addition, the said pin has a screw adjustment; a part of the shank that extends above the top of the arm being threaded and fitted with an adjusting nut s^{13} .

When it is required to introduce a stone between the pins for setting, the adjusting nut is slackened off so that the spring has free play upon the top pin, then the top arm is swung over into parallel relationship with the bottom blade and the extremity of the top pin is held in contact with the end of the bottom one by the spring thrust. The locking device (s^{11}) is then engaged to secure the two arms in parallel relationship, after which the top-pin s^5 is lifted against the spring to allow the stone to be inserted between the points of the two pins, when the spring exerts a sufficient pressure to main-

tain the stone in place while the pins are being adjusted for correctly positioning the said stone in the desired relationship to the bottom of the gaging in the lower blade. 5 As has already been stated, the whole of these operations are performed with the setting tool detached from the mold, which enables the operator to have the stone and the gaging-gap in full and clear view or observation during the setting or gaging operation.

The adjustment or setting having been completed, the setting-tool unit, with stone *in situ*, is transferred to the mold and positioned in the matrix by dropping the bottom blade into its seating-slot *d* and inserting the base-pin of the standard *s²* into the socket *e'* of its supporting bracket *e*. The stone is thereby registered or located exactly as required in the center of, and at the right height within, the matrix orifice, and then the chuck gear is operated so as to close the gripping jaws around the girdle of the stone. This done, and the stone being now firmly held in the matrix independently of the setting pins, the top arm of the setting tool is unfastened and swung outward (see Fig. 7) to take the top pin clear of the top of the mold.

30 Then the pouring gate *b* is applied to the top of the mold and the molten metal is run in for casting the dop onto and around the girdle of the stone, and when the metal has cooled, the chuck jaws are opened and retracted clear of the stone into their respective clearances *c* of the mold, and the setting tool is lifted out, bringing the dop and stone with it, and leaving the mold ready for the insertion of another tool and stone.

40 Having described my invention, what I claim and desire to secure by Letters Patent is:—

1. Dop-casting apparatus consisting of a setting-tool unit which is formed with a 45 gaging-gap whose shape is a replica or counterpart of the transverse sectional shape of the dop-casting matrix, and is provided with means for adjusting a stone relatively to the said gaging gap, and a casting-mold 50 unit embodying means which when the setting-tool unit is applied to the mold regis-

ters the gaging-gap of the tool unit with the casting matrix.

2. Dop-casting apparatus according to claim 1, wherein the setting-tool unit comprises a blade-like member wherein a V-shaped gaging-gap is formed, a supporting member to which the blade member is rigidly attached, a swing-over arm which is hinged relatively to the blade member, 60 screw-adjusting setting pins mounted in both the blade member and swing-over arm, and means for locking the swinging arm in parallel relationship to the blade member, with the two setting pins in alinement. 65

3. A setting-tool unit comprising the combination of parts specified in claim 2, wherein the screw adjusting setting pin is slidably mounted in the swing-over arm, and is influenced by a spring by the thrust of which 70 a stone placed between the two pins is gripped during the operation of setting the same by the screw adjustments.

4. Dop-casting apparatus according to claim 1, wherein the mold is formed with a 75 transverse slot, located in the plane of the mold axis, and adapted to serve as a seating for the reception of the gaging-gap member of the setting-tool unit; the mold-unit also being provided with means for locating the said setting-tool member within the said transverse seating in a position in which the gaging-gap registers with the mold-matrix. 80

5. Dop-casting apparatus according to 85 claim 1, wherein the casting-mold unit is combined with a chuck-mechanism which is disposed underneath the mold, and comprises a series of pivoted arms carrying stone-gripping jaws which engage clearances that radiate from the mold-matrix, and means whereby the said jaws may be simultaneously caused to enter the mold-matrix for engaging and gripping a stone that has been previously positioned in the 90 said matrix by the setting tool unit.

In testimony whereof I have affixed my signature in the presence of two witnesses.

WILLIAM J. DAVIDS.
